(57) CLAIM

The ornamental design for the hand held game, as shown and described.

DESCRIPTION

FIG. 1 is a top plan view of a hand held game;

FIG. 2 is a bottom plan view of the hand held game thereof;

FIG. 3 is a side elevational view of the one side of the hand held game thereof;

FIG. 4 is a side elevational view of the other side of the hand held game thereof;

FIG. 5 is an end view of one end of the hand held game thereof; and,

FIG. 6 is an end view of the other end of the hand held game thereof.

The broken line showing of font letters in FIG. 1 is for illustrative purpose only and forms no part of the claimed design.
